(No Model.)

A. B. REID.
TYPE WRITING MACHINE.

No. 449,296.

Patented Mar. 31, 1891.

UNITED STATES PATENT OFFICE.

ARTHUR B. REID, OF CHICAGO, ILLINOIS, ASSIGNOR OF ONE-HALF TO
LARSEN FILSTRUP, OF SAME PLACE.

TYPE-WRITING MACHINE.

SPECIFICATION forming part of Letters Patent No. 449,296, dated March 31, 1891.

Application filed July 1, 1889. Serial No. 316,252. (No model.)

To all whom it may concern:

Be it known that I, ARTHUR B. REID, a citizen of the Dominion of Canada, and a resident of the city of Chicago, in the county of Cook 5 and State of Illinois, have invented a certain new and useful Improvement in Type-Writing Machines, of which I declare the following, in connection with the accompanying sheet of drawings, to be a full, complete, and 10 accurate specification.

My invention relates to that class of type-writing machines in which the metallic types are placed near or at the extremity of metallic or other rods or arms and designed to be operated by a draw-bar and lever, so that the 15 types may strike at a common point, and in which a lever is operated by a key, which said lever by means of a connecting draw-bar operates the type-arm, and in which certain 20 mechanical connections exist, which are operated by the key-lever simultaneously with the operation of the type-arm, whereby upon the release from each depression of the lever the paper is caused to move a sufficient space to 25 receive the impression of the next type. In the action of such machines as constructed at the present time the operation of pressing a key downward depresses a corresponding lever. This lever draws a draw-bar downward, 30 which being connected with the type-arm throws the type up to the common striking-point upon the paper. The depression of the lever upon which the key is attached at the same time depresses a bar beneath it. Attached to this bar beneath the lever is a rod 35 connecting with certain other mechanism which differs somewhat in construction in the various machines, but which said mechanism by depression of the bar is placed in readiness to operate, and upon a release from the downward pressure of the lever the said mechanism moves the paper across the striking-point the necessary distance to receive the impression of the next succeeding letter, and 40 where it is necessary to leave a space between words a separate lever and key are used in most such machines, usually denominated a "space-key," which differs from the type-keys in that it does not connect with the type-arm, and 45 when the key is pressed downward operates

only upon the bar connected with the mechanism which moves the paper and moving the paper when the key is released in exactly the same manner and by the same means as by the release of one of the levers connected 55 with a type-arm.

The object of my invention is to so improve the action of type-writing machines in which the aforesaid method of spacing now exists that a space-key may not be necessary 60 therein to make the spaces between words when writing and to effect such improvement by the mechanism hereinafter described, or by such modification thereof as without departing from the substantial features of said 65 mechanism may be necessary for its adaptation to the different forms of type-writing machines to which it may hereafter be applied, and to enable a person operating a type-writing machine constructed with my improvement 70 herein described to accomplish the spacing between words by depressing a second time the key by which the type printing the final letter of the preceding word was actuated, or, in other words, my improved action 75 would enable the operator in writing the word "and" when striking the key by which the final letter "d" is printed to make the succeeding space after the word by a second depression of the same key with which the final 80 letter "d" was imprinted without releasing the finger therefrom.

The utility of my invention is to so improve such machines as I have hereinbefore generally described, upon which spacing is accomplished only by use of a separate space-key, so as to simplify the motions necessary thereon to effect spaces between words, reduce to a minimum the movements of the hands to acquire that end, and thereby increase the 85 rate of speed, which, next to legible writing, is the object most desired in type-writing machines. This result I accomplish by the mechanism hereinafter described.

In most type-writers (other than those constructed in conformity with my invention) the type-arm is operated by a draw-bar or push-bar directly connected therewith. In my invention I use a draw-bar and type-arm similar in structure to that heretofore used, but do 90

not make a fixed connection between the two, but instead thereof operate the type-arm by means of a clutch, cam, or similar mechanism attached to the draw-bar, which may engage and operate the type-arm by the depression of the key or not, as the operator desires, thus enabling the operator by a depression of the key to cause a letter to be imprinted and a movement of the paper and by a second depression of the same key to again move the paper-carriage without again imprinting the same letter.

In all type-writing machines operating upon the lever principle—that is to say, machines constructed with types affixed upon suspended arms and operated by draw-bars and levers to strike the types at a common point—the paper is held in a carriage which travels across the common point at which the types strike. The motive power which operates the paper-carriage is usually a spring, and the mechanism is somewhat different in the various machines; but a point of mechanical construction common to all such machines is that the draw-bars and connecting type-arms are operated by a series of parallel levers at or near the bottom of the machine, each of these parallel levers connecting with a draw-bar and type-arm upon which a type is affixed, and running transversely beneath these parallel levers is a universal bar, which from its position must be depressed by the said parallel levers or as well must be depressed by the depression of any one of the said levers. Attached to this bar is an arm, rod, or draw-bar which extends upward and is connected with the mechanism which operates the paper-carriage. Such mechanism, as I have before stated, differs in different makes of machines, but is common in its substantial operation thus far, that the depression of the universal bar and its subsequent elevation are necessary to operate the mechanism and cause the paper-carriage to travel the proper space for one letter. The elevation of the bar is usually attained by a spring exerting an upward energy. It therefore appears that of the details of the spacing mechanism my improvement makes no part, and for that reason I have omitted all description of such details.

The substantial principle of my invention is that of connecting the lever which sets the spacing mechanism in operation with a type-arm, or allowing the type-arm last actuated to become and remain disconnected from said lever at the will of the operator for and during the time which lever is actuated to operate the spacing mechanism.

The structure and operation of my improvement may be more fully shown and described by reference to the accompanying sheet of drawings, which is hereby made a part of this specification.

In the accompanying sheet of drawings, Figure 1 is a vertical sectional elevation of a type-writing machine constructed with my

improved action. Fig. 2 is a full-sized side elevation of the draw-bar, clutch, and type-arm in my improved action with the frame work cut away to show the internal structure, the dotted lines in this figure showing the draw-bar depressed and type-arm raised and the clutch at the releasing-point. Fig. 3 is a full-sized front elevation of the clutch and type-arm used in my improved action. Fig. 4 is a side elevation of the parts shown in Fig. 2, the outer frame-work covering the same, and in which the dotted lines indicate the clutch dropped back nearly to its engaging-point. Fig. 5 shows in side elevation a modified form of the construction of the draw-bar and type-arm.

In the several figures of said drawings like letters and numerals of reference indicate like parts.

A indicates the frame-work of the type-writing machine.

B B B B are the operating-keys of a type-writing machine.

D is one of the series of bars which are severally attached to the said parallel levers.

E is a suspended arm, at or near the lower extremity of which the printing-type is attached.

F is a printing-type attached to the arm E.

H is a universal bar extending beneath the entire series of parallel operating-levers, and is connected by a rod I with the propelling mechanism of the paper-carriage.

I is a connecting-rod extending upward from the outer extremity of bar H and connecting with certain mechanism, the function of which mechanism is to operate the paper-carriage upon the machine a certain distance each time that the key operating the lever C or any of its parallel fellows is released.

K is a circular or oval band forming part of the receptacle or basket into which the type-arms fall and against which they lie when not in operation.

L is a spring under lever C, which throws the lever back into position after depression and there holds it in position.

M is a part of the mechanism by which the paper-carriage is operated, and as this mechanism differs somewhat in different machines and forms no part of my invention other than as it is connected thereto by the rod I and universal bar H will not be further described herein.

N represents the position of the paper-carriage and roller, which is the common striking-point of the several types.

1 is a loop extending upward from the upper portion of the draw-bar D, the upper end of which passes through an eye in the hereinafter-described clutch.

2 is a forked clutch constructed of wire, bent at its center to form a double spiral, the two ends projecting therefrom nearly parallel, but slightly more divergent at their extremities and having their several extremities

hooked upward, the interior of the double spiral forming the eye through which the upper end of loop 1 passes.

3 is a barrel-pivot, through which clutch 2 passes at a point slightly below the spiral loops and forms the fulcrum from which a lever-action of said clutch is projected.

X is a slotted head affixed rigidly by a screw to the frame-work of the machine.

10 4 is a perpendicular eye passing through the slotted head X, in which the barrel-pivot 3 plays.

15 5 is a projection upon type-arm E, which may be engaged by the extreme ends of clutch 2.

6 is a pivot passing through slotted head X and upon which type-arm E is suspended.

20 The operation of my invention is as follows: To imprint a letter upon the paper, the key B is depressed by the finger. This depression draws draw-bar D downward.

25 The loop at the upper end of the draw-bar D passes through the double spiral coil in wire clutch 2 and draws the upper end of the wire

clutch downward until the pivot 3 strikes the bottom of the eye 4, which causes the lower bent

ends of clutch to engage the projection 5 upon arm E. This raises the type-arm until the type F reaches the common striking-point. Clutch

30 2 travels around the curved lower surface of projection 5 and releases itself when the type reaches the striking-point, whereupon the arm falls back into the basket against the band K by force of gravity, and if the key-lever is

35 then fully released and forced to its normal position by the upward energy of its spring the connecting-rod I is thereby driven upward and the clutch 2 connected thereto thereby operated upon its pivot and caused to

40 regain its position in rear of type-arm E, in readiness to again clutch and operate said type-arm. The depression of the lever C, pressing upon the universal bar H, draws rod I downward, which, connecting with the mech-

45 anism M, prepares the mechanism by which the paper-carriage is operated to work, and upon releasing or partially releasing the pressure from the key B the lever C is thrown upward by spring L and the bar H thereby

50 released, which enables the mechanism operating the paper-carriage to move the carriage one space.

Should it be desired to make a space after the letter last imprinted, the pressure of the

55 finger is retained upon the key B and the bar C allowed only to partially regain its normal position, the clutch 2 being allowed to fall back to a point in front of projection 5, as indicated by dotted lines in Fig. 4, at which

60 point it cannot clutch or operate the type-arm E, the key B being again depressed, while the clutch is at this point, by which second depression of key B lever C again depresses bar H and operates the connecting mech-

65 anism, but does not operate the type-arm E, and when lever C is again released and allowed to take its normal position two spacings will

then have been made after the imprint of the letter, and the number of spacings may be increased by repeated depression of the key, 70 taking care that the key is not released so as to allow the clutch to recede to a position at which it may engage the projection upon the type-arm.

75 A substantial equivalent for the method of operating hereinbefore described, and which I desire to fully claim in this specification, is shown on Fig. 5. In the construction there shown I construct the type-arm E with a cam-shaped extension extending backward from the point at which the arm is pivoted to the machine and construct the upper end of draw-bar I with an overhanging hook to engage the upper surface of the said cam, so that the depression of the draw-bar may operate upon upper surface of the cam, thereby raising type-arm to the desired point, as indicated by dotted lines, at which point the cam is released and cannot be again engaged until the draw-bar is again elevated to a point at 90 which the hook may ride upon the cam.

85 I do not confine myself in my invention to the specific form of clutch or cam shown by which the type-arm may be engaged, or the specific location thereof, but reserve the right 95 to vary the form or position thereof for the purpose of connecting and disconnecting the key-bar and type-arm or the application of any known and common mechanism for that purpose, the principle of my invention being the 100 construction of the key-bar without a fixed connection to the type-arm and the introduction of intervening mechanism susceptible of causing said key-bar and type-arm to coact or not, according as the key bar or lever is 105 raised to its normal point or not.

I claim as my invention and desire to secure a patent for the following:

1. In a type-writing machine, a type-arm supplied with metal or other type at or near its lower extremity, said type-arm constructed with a cam-shaped projection, as indicated by 5, in combination with an operating-clutch so constructed as to intermittently engage said cam-shaped projection, substantially in 115 manner and form herein specified.

2. In a type-writing machine, the combination of a key, as indicated by B, a lever, as indicated by C, a spring, as indicated by L, a draw-bar, as indicated by D, a connecting-loop, as indicated by 1, a forked clutch, as indicated by 2, and an independent type-arm, as indicated by E, all combined to act and co-operate substantially in the manner and for the purpose herein specified. 120

3. In a type-writing machine, an independent type-arm constructed with a cam upon its shank, an operating-rod, and an intervening clutch, as specified. 125

4. In a type-writing machine, a disconnected type-arm having a projection 5, a draw-bar and clutch, said clutch connected to the draw-bar by a loop, as indicated by 1, passing through an eye at upper end of clutch, 130

4

said clutch passing through and operating upon a barrel-pivot, as indicated by 3, and said pivot playing in a perpendicular eye, as indicated by 4, said clutch so constructed as 5 to engage the projection (indicated by 5) upon type-arm when operated by depression of draw-bar, and as depression continues the forked extension of said clutch to travel around the lower curved surface of said projection as the type-arm raises, releasing its engagement upon said projection when the type attached to said arm reaches the striking or printing point, and said clutch being

so constructed and combined with the above-specified parts that it may be allowed to re- 15 cede nearly back to its original position without again engaging the said type-arm, all substantially in manner, structure, and operation as above set forth, shown, and described.

In witness whereof I have hereunto set my 20 hand, in the presence of two subscribing witnesses, this 29th day of June, 1889.

ARTHUR B. REID.

In presence of—

LENA YORK,
W. KNOX HAYNES.
